UNITED STATES PATENT OFFICE.

STANLEY REYNOLDS, OF ROCHESTER, NEW YORK.

DESIGN FOR THE ORNAMENTATION OF BURIAL-CASKETS.

SPECIFICATION forming part of Design No. 14,496, dated December 18, 1883.

Application filed October 19, 1883. Term of patent 7 years.

To all whom it may concern:

Be it known that I, STANLEY REYNOLDS, a citizen of the United States, and a resident of Rochester, in the county of Monroe and State of New York, have invented a certain new and useful Design for Burial-Caskets; and I do hereby declare that the following is a full, clear, and exact description thereof, which will enable others skilled in the art to which it ap-

10 pertains to make and use the same, reference being had to the accompanying drawings, which form a part of this specification, and in which—

Figure 1 is a perspective view of a casket 15 decorated with my new design. Figs. 2, 3, and 4 are views of some slight variations in the design; and Fig. 5 is a section on line $x x$, Fig. 2.

Similar letters of reference indicate corresponding parts in all the figures.

My new design is especially intended for the decoration of burial-caskets; and it consists of ornamentation forming sectors of a circle, as shown in the drawings, in which the letter 25 A indicates the casket, and B the design, which forms a circle-sector or an entire circle

composed of a number of sectors, C, having beveled edges forming radial gutters D between them, having circular or segmental molding E near the center, a circular or segmental row of beads, F, inside the molding, and a central circular or sector-shaped plate, G.

These ornamentations may be arranged upon the sides, ends, or top of the casket, and form entire circles or sectors, as desired.

35

What I claim is—

In a design for a coffin, the herein-described ornamentations, consisting of sectors having beveled edges forming radial gutters, and arranged in a circle or circle-sector, a circular 40 or segmental molding near the center of the design, a circular or segmental row of beads inside the molding, and a circular or sector-shaped center plate, as shown and described.

In testimony that I claim the foregoing as 45 my own I have hereunto affixed my signature in presence of two witnesses.

STANLEY REYNOLDS.
